TIRE

Daniel E. Schuster, North Royalton, Ohio, assignor to
The Goodyear Tire & Rubber Company, Akron, Ohio, a corporation of Ohio

Filed June 26, 1969, Ser. No. 17,887

Term of patent 14 years

Int. Cl. D12—14

U.S. Cl. D90—20

The figure is a perspective view of a tire showing my new design, it being understood that the design is repeated throughout the circumference of the tire, the opposite side being substantially the same as that shown.

I claim:

The ornamental design for a tire, substantially as shown and described.
